RAILWAY TRUCK

Glenn F. Couch, Rochester, N. Y., assignor to
The Symington-Gould Corporation, Rochester,
N. Y., a corporation of Maryland

Application November 2, 1934, Serial No. 751,202

15 Claims. (Cl. 105—197.1)

This invention relates to railway vehicles and, more particularly, to the construction of the side frames, bolsters and spring nests thereof for supporting such bolsters from said frames.

5 The principal object of my invention, generally considered, is the development of a railway truck in which the side frames thereof are quickly detachable and in which the ultimate load application to said frames is close enough to the journal boxes to materially reduce the bending moments.

10 Another object of my invention is the provision of a railway truck in which the bolsters are supported from the side frames thereof by both coil and leaf springs, the points of support of said springs on said frames being outwardly spaced from the transverse central planes of said frames to reduce the bending moments thereon.

15 A further object of my invention is the provision of a railway truck in which the ends of the bolster are received in frames or rest on saddles which are, in turn, supported by leaf or semi-elliptic springs therebeneath and coil or helical springs at the sides thereof, said leaf springs having their ends supported beneath the guide columns and said columns diverging downwardly and serving to support and partially house said coil springs.

20 A still further object of my invention is the provision of a railway truck in which the bolster is supported by both coil and leaf springs, and in which provision is made for relative angling between said bolster and the journal boxes associated with said frames, either by movement between the boxes and frames, or by movement between 25 the frames and bolster.

25 An additional object of my invention is the provision of a bolster of a railway truck, the ends of which engage frames which are, in turn, supported by springs from the side frames, said bolster being locked in position with respect to said frames by means insertable from below and preventing disengagement of said bolster from said frames while allowing a desired amount of angling therebetween.

30 Other objects and advantages of the invention relating to the particular arrangement and construction of the various parts will be made apparent as the description proceeds.

35 Referring to the drawings illustrating my invention, the scope whereof is defined by the appended claims:—

40 Figure 1 is a partial side elevation and partial central longitudinal sectional view of a fragmentary portion of a railway truck embodying my invention.

Fig. 2 is a partial plan of the truck shown in Figure 1.

Fig. 3 is a fragmentary transverse sectional view on the line 3—3 of Figure 1, looking in the direction of the arrows.

Fig. 4 is a fragmentary longitudinal sectional view on the line 4—4 of Fig. 2, looking in the direction of the arrows.

Fig. 5 is a fragmentary horizontal sectional view on the line 5—5 of Fig. 4, looking in the direction of the arrows.

Fig. 6 is a partial side elevation and partial central longitudinal sectional view of a fragmentary portion of a railway truck illustrating another embodiment of my invention.

Fig. 7 is a fragmentary plan of the embodiment of my invention illustrated in Fig. 6.

Fig. 8 is a fragmentary transverse sectional view on the line 8—8 of Fig. 6, looking in the direction of the arrows.

Fig. 9 is a fragmentary side elevational view corresponding to Fig. 6, but showing the bolster in elevated position while being connected or disconnected with respect to the associated frame.

Referring to the drawings in detail, like parts being designated by like reference characters, and first considering the embodiment of my invention illustrated in Figs. 1 to 5, inclusive, there is shown a portion of a railway vehicle or truck comprising side frames 1, only one of which is illustrated, 30 each side frame having a compression member or portion 2, a tension member or portion 3, and spaced connecting struts, bolster guide columns, or portions 4 spacing intermediate portions of said compression and tension members, and leaving a bolster or window opening 5 therebetween.

35 The tension member 3 beneath the window opening is formed with horizontal shelves or abutment portions 6 normally engaged by the ends of the leaf or semi-elliptic spring 7 disposed in the lower portion of the window opening 5 and, in turn, supporting a frame or saddle member 8 having a downwardly opening pocket 9 receiving the upper portion of the spring band 10, thereby preventing undesired displacement therebetween.

40 The saddle member 8 has a normally horizontal portion 11 on which rests the adjacent end of the bolster 12 and side portions 13 normally embracing the end portion of the bolster therebetween and embraced between front and rear 50 guide lugs 14 and 15 on said bolster, thereby serving to hold the bolster assembled therewith.

45 The extremities of the U-shaped saddle 8 are provided with curved bearing portions 16 which engage cooperatively curved bearing portions 17 55

on upper spring caps 18 of coil or helical springs 19. Said springs 19 are, in turn, supported on lower caps 20 having curved bearing surfaces 21 receiving transverse abutment portions 22 which 5 connect the flanges 23 of the U-shaped columns 4 and are provided with correspondingly curved upper surfaces 24.

On account of the columns 4 being U-shaped and the springs 19 being supported on integral portions which connect the sides or flanges thereof, 10 said columns serve to partially house said springs as well as the end portions of the semi-elliptic springs 7 which extend between the flanges 23 of said guide columns. In the present embodiment, 15 said columns 4 diverge downwardly and outwardly and the springs 19 have a corresponding inclination. This construction facilitates assembly of the parts and makes it possible to use a semi-elliptic spring 7 of the desired length. 20 Upon the load on the bolster 12 varying, the springs 7 and 19 are compressed to a greater or less extent and the saddle 8 moves up or down between the guiding portions 25 of said columns, lateral movement of said saddle with respect to 25 said columns being limited by the flanges 26 of said saddle received between the flanges 23 of the guide columns 4, the portions of said saddle adjacent and laterally outward of said flanges 26 forming ribs engaging the guiding portions 25 30 for limiting longitudinal movement.

The frame 8 has jaws at its ends providing downwardly opening pockets 27 receiving separable journal boxes 28. Provision is made for angling of the journal boxes with respect to the 35 frame without loss of bearing area in the jaws by forming the inner surfaces of said jaws cylindrically concave, as indicated at 29, and the corresponding surfaces of the box correspondingly convex, as indicated at 30, thereby providing for 40 the desired flexibility of the truck.

From the foregoing disclosure, it will be seen that I may employ a standard bolster 12 inasmuch as the columns 4 are spread apart sufficiently to allow the sides 13 of the saddle 8 to 45 be interposed between the sides of the bolster and the guiding portions 25 of the guide columns. Disconnection of the frames from the bolster is readily permitted, as will be understood, by raising the bolster and saddle sufficiently to permit removal of the springs and then dropping the saddle so as to allow the frames to be removed from the 50 ends of the bolster. The abutment portions 22 are desirably spaced a distance greater than the maximum dimension of the saddle longitudinally of 55 the frame so that said saddle may be dropped between said abutments on removing the spring 7, without interference.

In order to prevent undesirable lateral shifting of the spring 7, the abutment portions 6 which 60 the ends of said spring engage are desirably provided with lugs 31 receiving the ends of the spring therebetween. It will be noted that I do not show a spring plank, but such may, of course, be used, if desired. It will also be noted that the 65 journal boxes, only one of which is illustrated, may be locked in place in any desired manner, as by means of latches 32, as shown.

Referring now to the embodiment of my invention illustrated in Figures 6 to 9, inclusive, 70 there is shown a portion of a railway vehicle or truck comprising side frames 1^a, only one of which is illustrated, each sideframe having a compression member 2^a, a tension member 3^a, and spaced connecting columns 4^a spacing intermediate portions of said compression and ten-

sion members and leaving a bolster or window opening 5^a therebetween.

The tension member 3^a beneath the window opening is, as in the previous embodiment, formed with shelves 6^a normally engaged by the ends 5 of the leaf or semi-elliptic spring 7^a disposed in the lower portion of the window opening 5^a and, in turn, supporting a frame 8^a having a downwardly opening pocket 9^a receiving the upper portion of the spring band 10^a for preventing undesired displacement therebetween. The bolster supporting member 8^a, in the present embodiment, is formed as a generally rectangular frame rather than a U-shaped saddle, thereby greatly increasing the strength against bending forces. 10 Said member 8^a has a normally horizontal portion 11^a on which rests the adjacent end of the bolster 12^a, and side portions 13^a normally embracing the end portions of the bolster therebetween and engaged by rear guide lugs 15^a on said bolster. 20

The upper ends of the side portions 13^a of the frame 8^a are joined by the upper normally horizontal portion 33, the end portions of which are provided with curved bearing lugs 16^a which engage cooperatively curved bearing portions 17^a 25 on upper spring caps 18^a of coil or helical springs 19^a. Said springs 19^a are, in turn, supported on lower caps 20^a desirably formed and supported as in the preceding embodiment on abutment portions 22^a which connect the flanges 23^a of 30 the guide columns 4^a.

As in the preceding embodiment, the columns partly house the coil springs and the ends of the semi-elliptic spring and diverge downwardly and outwardly, the springs 19^a having a corresponding inclination, thereby facilitating assembly and disconnection of the parts, as explained in connection with the preceding embodiment. The frame 8^a guides the end of the bolster and is, in turn, guided by the guiding portions 25^a of the 40 columns 4^a, as in the preceding embodiment.

In the present embodiment, I contemplate the provision of journal boxes integral with the end portions of the frame, which journal boxes and end portions are not shown, as they may be of conventional construction. Flexibility of the truck is effected at the connection between the bolster and frame rather than at the connections between the journal boxes and frame, said flexibility being provided by forming the surfaces of the bolster 12^a, which are engaged by the upright portions 13^a of the frame 8^a, cylindrical and the corresponding surfaces of said portions 13^a curved to correspond, the axis of said cylindrical surfaces being in the central longitudinal 50 vertical plane of the bolster. The cylindrical bolster surfaces are designated by the reference character 34, and the corresponding cooperating frame surfaces by the reference character 35. The surfaces 34 and 35 terminate at their outer 55 ends in portions 36 and 37 which together provide cylindrical pockets receiving locking members 38. Each locking member desirably comprises a normally vertical cylindrical body 39 and a lower laterally extending lug 40, and is initially 60 inserted, as illustrated in Figure 9, with the lug extending outward, the frame 8^a being provided with an elongated aperture 41 adapted to receive said body and lug portions. When the locking member 38 has been inserted so that the 65 lug 40 lies above the horizontal portion 11^a of the frame, the lug is then turned so as to point inward or toward the other locking member (not illustrated), while the bolster is elevated, as 70 illustrated in Figure 9, so that when the bolster is 75

dropped to position, as shown in Figure 6, the lug portion 40 is received in a pocket 42 in the lower surface of the bolster and securely held in place. Sufficient clearance is provided between the locking members 38 and the bolster to allow for the desired flexibility or angling in a horizontal plane between said bolster 12^a and frame 8^a while preventing undesired displacement or withdrawal of the bolster.

10 From the foregoing disclosure, it will be seen that I do not propose to employ a standard bolster in the embodiment of Figures 6 to 9, inclusive, on account of the provision for angling of said bolster with respect to the supporting frame. The parts 15 of this embodiment may be assembled and disconnected as described in connection with the first embodiment, with the exception of the connection and disconnection of the bolster with respect to the supporting frame 8^a which is effected by the use of the latches, previously described, rather than by the mere fitting together 20 of the bolster and saddle member, in accordance with the first embodiment.

Although preferred embodiments of my invention have been disclosed, it will be understood 25 that modifications may be made within the spirit and scope of the appended claims. It will also be understood that the form of my invention illustrated in Figures 6 to 9, inclusive, may correspond 30 with that of the first embodiment except as specifically described as being different. It will also be understood that although this embodiment may involve journal boxes integral with the side frames yet, if desired, separate journal boxes may 35 instead be employed as in connection with the first embodiment.

I claim:—

1. In a railway truck, in combination, a side frame formed with compression and tension members spaced at intermediate portions by guide 40 columns, leaving a bolster opening therebetween, spring means disposed in the lower portion of said opening and spanning the distance between said columns, other spring means supported directly by said frame and disposed directly above 45 the end portions of said first-mentioned spring means, and a bolster disposed above said first-mentioned spring means and between said second-mentioned spring means and resiliently supported by both.

2. In a railway truck, in combination, a side frame formed with compression and tension members spaced at intermediate portions by guide 50 columns extending diagonally upward and toward one another from said tension member, leaving a bolster opening therebetween, spring means disposed in the lower portion of said opening, other spring means disposed above said first-mentioned spring means, at least partially 55 housed in said columns, and acting diagonally upward and toward one another, and a bolster disposed above said first-mentioned spring means and between said second-mentioned spring means and resiliently supported by both.

65 3. In a railway truck, in combination, a side frame formed with compression and tension members spaced at intermediate portions by guide columns, leaving a bolster opening therebetween, a semi-elliptic spring disposed in the lower portion of said opening and spanning the distance 70 between said columns, helical springs acting directly on said columns and disposed directly above the end portions of said semi-elliptic spring, and 75 a bolster disposed above said semi-elliptic spring

and between said helical springs and resiliently supported by both.

4. In a railway truck, in combination, a side frame formed with compression and tension members spaced at intermediate portions by guide 5 columns, leaving a bolster opening therebetween, a spring supported by said frame and disposed in the lower portion of said opening, with its ends housed in said guide columns, springs disposed above the ends of said first-mentioned spring and 10 partially housed in, and directly supported by, said columns, and a bolster with an end portion received in said opening and supported by means of all of said springs acting in parallel.

5. In a railway truck, in combination, a side 15 frame formed with compression and tension members spaced at intermediate portions by guide columns which extend diagonally downward and outward from said compression member to said tension member, leaving a bolster opening there- 20 between, a spring supported by said frame and disposed in the lower portion of said opening with its ends housed in said guide columns, springs disposed above the ends of said first-mentioned spring and 25 partially housed in said columns, and a bolster with an end portion received in said opening and supported by all of said springs.

6. In a railway truck, in combination, a side frame formed with compression and tension members spaced at intermediate portions by guide 30 columns, leaving a bolster opening therebetween, a spring supported on said tension member and other springs directly supported on said columns, a frame supported in turn by all of said springs 35 acting in a generally upward direction, and a bolster resting on said frame.

7. In a railway truck, in combination, a side frame formed with compression and tension members spaced at intermediate portions by guide 40 columns, leaving a bolster opening therebetween, a semi-elliptic spring supported by means of said tension member, coil springs directly supported by means of said columns and with their axes disposed generally parallel to the axes of the associated columns, a frame member supported in 45 turn by all of said springs, and a bolster resting on said frame member.

8. In a railway truck, in combination, a side frame formed with compression and tension members spaced at intermediate portions by guide 50 columns, leaving a bolster opening therebetween, a semi-elliptic spring supported on said tension member and provided with a spring band, a casting with a downwardly opening pocket receiving the upper portion of said band and supported by 55 said spring, said casting having side portions, a bolster resting on said casting and formed with lugs embracing said side portions for holding said bolster in place, said side portions having upper outwardly extending portions, and coil springs 60 acting on said upper portions to serve as additional means for supporting the bolster, said guide columns having transverse portions disposed above the ends of said semi-elliptic spring and serving to support said coil springs.

65 9. In a railway truck, in combination, a side frame formed with compression and tension members spaced at intermediate portions by guide columns, leaving a bolster opening therebetween, a bolster received in said opening, a casting 70 formed with a portion underlying said bolster and side portions interlocked therewith, a spring supported on said tension member and engaging said underlying portion, and other springs supported on means disposed at a fixed elevation with 75

respect to said guide columns and engaging said side portions.

10. In a railway truck, in combination, a side frame formed with compression and tension members spaced at intermediate portions by guide columns, leaving a bolster opening therebetween, a spring supported by means of said tension member, a casting resting on said spring, a bolster resting on said casting, said casting having sides extending upwardly from the ends of a normally horizontal bolster supporting portion and embracing said bolster therebetween, the inner surfaces of said sides and the adjacent surfaces of said bolster being coaxially curved to allow for relative horizontal angling therebetween, said casting having portions extending outwardly from its sides, and springs supportingly engaging said outwardly extending portions and supported by abutments disposed at an elevation fixed with respect to said frame.

11. In a railway truck, in combination, a side frame formed with compression and tension members spaced at intermediate portions by guide columns, leaving a bolster opening therebetween, a spring supported by means of said tension member, a casting resting on said spring and a bolster resting on said casting, said casting having sides extending upwardly from the ends of a normally horizontal bolster supporting portion and embracing said bolster therebetween, the inner surfaces of said sides and the adjacent surfaces of said bolster being coaxially curved to allow for relative horizontal angling therebetween, said sides having outward extensions disposed between portions of said guide columns, and springs partially housed in said columns, supported thereby, and acting on said extensions to assist in the support of said bolster.

12. In a railway truck, in combination, a side frame formed with compression and tension members spaced at intermediate portions by guide columns, leaving a bolster opening therebetween, a casting disposed in said opening, springs supported on said frame and, in turn, supporting said casting, and a bolster supported on said casting, the latter having sides, extending upwardly from the ends of a normally horizontal portion directly underlying said bolster, and embracing said bolster therebetween, the inner surfaces of said sides and the adjacent surfaces of said bolster being coaxially curved to allow for relative horizontal angling therebetween, said surfaces merging at their outer edges into concave surfaces defining a generally cylindrical aperture, and a locking member received in said aperture for preventing undesired removal of said bolster from the casting.

13. In a railway truck, in combination, a side

frame formed with compression and tension members spaced at intermediate portions by guide columns, leaving a bolster opening therebetween, a bolster supporting casting disposed in said opening, a bolster with an end portion received in said casting, and means for locking said bolster to said casting comprising a generally cylindrical member received in a pocket defined by opposed concave surfaces on said casting and bolster, said member having a laterally extending lug normally locked in position by being disposed between the bolster and casting.

14. In a railway truck, in combination, a side frame formed with compression and tension members spaced at intermediate portions by guide columns, leaving a bolster opening therebetween, resilient means supported on said frame, a casting resting on said resilient means and having sides extending upwardly from the ends of a normally horizontal bolster-supporting portion and embracing said bolster therebetween, the inner surfaces of said sides and the adjacent surface of said bolster being coaxially curved to allow for relative horizontal angling therebetween, the ends of said frame having downwardly opening jaws defining pockets, journal boxes received in said pockets, the portions of said jaws defining the sides of said pockets and the adjacent sides of said boxes being coaxially curved to allow for horizontal angling between said boxes and frame to correspond with the angling permitted between said bolster and the supporting casting.

15. In a railway truck, in combination, a side frame formed with compression and tension members spaced at intermediate portions by guide columns, leaving a bolster opening therebetween, resilient means supported on said frame, a casting resting on said resilient means and a bolster resting on said casting, said casting having sides extending upwardly from the ends of a normally horizontal bolster-supporting portion and embracing said bolster therebetween, the inner surfaces of said sides and the adjacent surfaces of said bolster being coaxially curved to allow for relative horizontal angling therebetween, said casting having flange portions extending longitudinally of the frame and away from said bolster, said guide columns having flange portions extending longitudinally toward said bolster and embracing said casting flange portions therebetween, the latter flange portions having ribs extending outwardly and laterally of the side frame and overlying the inner edges of said guide column flanges to provide for holding said casting in place between said guide columns while allowing for vertical movement thereof.

GLENN F. COUCH.
